United States Patent Office

Des. 219,844
Patented Feb. 2, 1971

219,844

AMPHIBIOUS AIRCRAFT

Cornelius Biemond, 105 S. 14th St., Ord, Nebr. 68862

Filed July 14, 1969, Ser. No. 18,196

Term of patent 14 years

Int. Cl. D12—07

U.S. Cl. D71—1

Dec. 219,844

PAGE 2

FIG. 2.

FIG. 3.

Des. 219,844

PAGE 5

FIG. 4.

FIG. 5.

FIG. 6.

FIG. 7.

FIG. 8.

FIG. 1 is a perspective view showing the design of the amphibious aircraft in an attitude of flight;

FIG. 2 is a bottom plan view thereof;

FIG. 3 is a top plan view thereof;

FIG. 4 is a left elevational view thereof;

FIG. 5 is a left elevational view thereof with landing gear extended;

FIG. 6 is a front elevational view thereof with landing gear extended and pontoons retracted;

FIG. 7 is a rear elevational view thereof with landing gear retracted and pontoons extended;

FIG. 8 is a rear elevational view thereof with landing gear extended and pontoons retracted.

I claim:

The ornamental design for an amphibious aircraft, as shown and described.
